UNITED STATES PATENT OFFICE.

HARRY G. WEBSTER, OF CHICAGO, ILLINOIS, ASSIGNOR TO MILO G. KELLOGG, OF CHICAGO, ILLINOIS.

COMBINED TELEPHONE EXCHANGE AND ALARM SYSTEM.

No. 825,685.

Specification of Letters Patent.

Patented July 10, 1906.

Application filed October 17, 1904. Serial No. 228,756.

To all whom it may concern:

Be it known that I, HARRY G. WEBSTER, a citizen of the United States, and a resident of Chicago, county of Cook, and State of Illinois, have invented certain new and useful Improvements in a Combined Telephone Exchange and Alarm System, of which the following is a full, clear, concise, and exact description, reference being had to the accompanying drawings, forming a part of this specification.

My invention relates to systems in which line-circuits extending from subscribers' stations to a telephone-exchange and adapted for interconnection thereat are utilized for the transmission of special fire, burglar, and other alarm signals in addition to their ordinary telephonic use.

The object of my invention is to provide an improvement upon the system illustrated and described in my application, Serial No. 204,978, filed April 26, 1904. In said application I have illustrated an organization in which the line-circuit is at all times available for the transmission of an alarm-signal and in which the alarm-sending and alarm-receiving apparatus does not cause any interference with telephonic signaling or conversation except upon the sending of an alarm-signal when the telephonic requirements may be disregarded. In such a system it is desirable that any accidental grounding of either limb of the telephone-line be automatically indicated at the alarm-receiving station, and it is preferable that this ground indication be given by means of an indicator distinct and separate from that which indicates an alarm-signal, and it is also desirable that the accidental grounding of either line-limb shall not cause the actuation of the alarm-indicator.

The improvement of my present invention consists in improving means for securing this ground indication in such a system as I have outlined, and it is in this respect a species under the generic invention set forth in the above application.

Other advantages of my improved system will be apparent to those skilled in the art from the following description.

In a preferred form of my present invention I associate with that line-limb leading from the "live" or active side of the central-

office-battery an electromagnet which serves when intermittently deenergized to cause the actuation or display of an alarm-signal, and I associate with that line-limb leading to the return side of the central-office battery an electromagnet adapted to control the display of the ground-indicator. The return side of this central battery has the customary connection to ground. The circuit of these electromagnets is normally closed through the two line-limbs and a resistance or impedance in bridge of the limbs at a point beyond the alarm-sending mechanism. This alarm-sending mechanism may be of the nature of the ordinary "make-and-break" apparatus of the ordinary district telegraph-box or of other construction, so arranged as to break and make a circuit of the line-limbs in a predetermined manner, and the normally closed contact or contacts of this device may be included in the circuit of the line-limbs at a point intermediate of the aforesaid electromagnets and the bridged impedance. The current which normally flows through the electromagnets and the line-limbs while of sufficient strength to energize the electromagnets is not of sufficient strength to interfere with the proper operation of the telephone-exchange signals. When the telephone is in use, the current which then flows through the line-limbs and the substation apparatus has a considerably higher value than the normal current; but inasmuch as the electromagnets referred to are already energized this increased current does not change the normal condition of the alarm-indicating or ground-indicating mechanism. If under the normal condition of the line or during the use of the telephone an alarm-signal is to be given, the interruption of the circuit of the line-limbs by the make-and-break device deprives both electromagnets of current, causing an alarm indication at the alarm-receiving station, as will be hereinafter described. It will also be seen that if under either of the conditions stated the circuit of the line-limbs becomes accidentally grounded at a point intermediate of the two electromagnets, a short circuit will be formed between the point of grounding and the return side of the central-office battery and that while the electromagnet controlling the alarm-indicating device will still receive cur-

rent through its winding the winding of the magnet controlling the ground-indicator will be deprived of current by this short circuit and the magnet consequently deenergized. 5 These electromagnets are preferably relay-magnets controlling by means of their contacts local circuits which include the alarm-indicating and ground-indicating devices. The alarm-indicating device may be in the 10 form of an ordinary telegraphic register or other suitable mechanism adapted to respond to the interruptions of the make-and-break alarm - sending mechanism. The ground-indicating device may be in the form 15 of an electromechanical signal or preferably may consist of a small incandescent lamp which by its illumination indicates the presence of an accidental ground upon the circuit of the line-limbs. My invention also 20 comprises means by which these electromagnets with their associated signal-indicating mechanism may be brought into association with any line of the telephone system in a systematic and workmanlike manner 25 without disturbing the permanent wiring.

The invention will be further illustrated and described in the accompanying drawings, in which—

Figure 1 is a diagram illustrating a preferred form of my invention in which two subscribers' lines are shown extending in metallic circuit from the substation to a central-battery telephone-exchange switchboard of the two-wire type, together with the customary connecting-cord and accessory apparatus. 30 Fig. 2 illustrates a modification of the local-circuit apparatus associated with the two relay-magnets. Fig. 3 illustrates my invention in a switchboard system of the two-wire type, the relay-magnets being in bridge of the two line-limbs rather than serially included therein, as in Fig. 1. Fig. 4 indicates a well-known cord connecting apparatus adapted for association with the line-circuit 40 of the system indicated in Fig. 3. Fig. 5 indicates means for associating the electromagnets and their associated mechanism with any telephone-line of the system without disturbing the permanent wiring.

50 Like characters refer to like parts in the several drawings.

Referring to Fig. 1, the subscribers' stations A and B are provided with the usual apparatus adapted, preferably, for use with a central source of current-supply and comprising a receiver *r* and transmitter *t* in a circuit which normally stands open at the hook-switch *h*, the bell *b* and condenser *c* being in permanent bridge of the line. While I have 55 thus illustrated one particular form of substation arrangement, it will be apparent to those skilled in the art that numerous other arrangements may be equally well employed in my invention, and I therefore do not wish 60 to be limited to the particular one shown.

The limbs 1 and 2 of the line extend to the central office and are there connected, limb 1 through armature 7 and contact 79 of the cut-off relay 3 and through the winding of relay 4 to the active side of the battery C and limb 2 through armature 6 and its back contact to the return side of the same battery. The subscriber in calling raises his receiver and completes the low-resistance circuit, including his transmitter and hook-switch contact, to actuate the relay 4, lighting his line-lamp 5. Upon the insertion of an answering-plug *P* the operation of relay 3 breaks the normal connection of the line-limbs through relay 4 and armature 6 to the battery C, thus 70 extinguishing the line-lamp, and connects them to the spring-jacks 8 and thence to strands 9 and 10 of the cord-circuit. Current is now supplied to the line A from battery C through relays 13 and 14, which control the circuit of the supervisory lamp 17, the lamp remaining dark as long as current flows through both relays. The operator tests, plugs in, and rings a wanted subscriber in the usual way with calling-plug *O* 80 and ringing-key *g g*. While ringing, the relay 3 is energized by current from battery E and generator G, and after the ringing-key is released relay 16 of the cord-circuit and relay 3 of line B are energized by current from 85 battery D. The relay 16 when thus actuated cuts off the test-relay 19 and completes the circuit of strand 11 through its contacts and also completes the circuit of supervisory lamp 18. When the called subscriber 90 answers, current is furnished his instrument through relays 15 and 16, and the energization of relay 15 opens the circuit of lamp 18, causing its effacement as long as the subscriber's hook-switch contact remains closed. 95 The subscribers are now able to converse over cord-strands 9 11 and 10 12, which include the condensers *d d*. The hanging up of both receivers deprives the relays 13 and 100 15 of current, thus allowing them to complete 105 the circuits of lamps 17 and 18, which being illuminated constitute the disconnect-signal. This is the regular telephonic operation of the system, as will be well understood by those skilled in the art, and is not interfered 110 with by the presence of the alarm apparatus associated with any of the lines. Those lines which are to be utilized for alarm service are provided with magnets *F* and *F'*, included in 115 limbs 1 and 2, respectively, and in the structure of Fig. 1 these relays are so arranged that their windings will present no objectionable impedance to the rapidly-alternating telephonic currents, either by means of the bridged condensers 24 and 25 or in any other 120 well-known manner. These relays, as will be hereinafter explained, control mechanism for causing alarm-signals and ground-signals 125 to be indicated at the alarm-receiving station. At the alarm-sending station or other 130

convenient point a resistance i is provided in bridge of the two line-limbs, this-resistance being preferably inductive resistance and so proportioned that the current-flow there-through over the two line-limbs shall be sufficient to energize the relays F and F' , but will be insufficient to interfere with the regular operation of the relays 4, 13, or 15 of the telephone-exchange system. Alarm-sending apparatus M is provided at a point intermediate of the bridged resistance and the magnets F and F' , which may be of the character of the well-known district messenger-box or similar apparatus adapted to be released manually or automatically, and this mechanism controls by its contacts the circuit of the two line-limbs. In the diagrammatic illustration of the drawings the make-and-break wheel n is normally prevented from revolving through the engagement of stop 22 with releasing-arm 21, the said arm being held in its position through the attraction of magnet m , which is included in the circuit of battery 20, together with the thermostatic or other circuit-breaking devices, (indicated at f .) In case an alarm is to be given the opening of this circuit, as indicated at f' in connection with line B , causes the de-energization of magnet m , allowing the arm 21 to be retracted by its associated spring, thus disengaging stop 22 and allowing the revolution of the make-and-break wheel n . As this wheel revolves the projections upon its periphery will cause limbs 1 and 2 to be interrupted at contacts 23 in accordance with a predetermined code, as will be well understood by those skilled in the art. This portion of the structure is shown in its normal position at line A , while at line B it is shown in operation. As has been pointed out, the magnets of the relays F and F' are normally energized by the comparatively weak current which flows through resistance i . When the subscriber calls by removing his receiver, the increased current-flow which then energizes relay 4 maintains the energization of the aforesaid magnets. When the line is switched for conversation, the magnets are then energized by current flowing through relays 13 and 14 or 15 and 16, and when the ringing-key is actuated the energization of the magnets is maintained by current from battery E and generator G . The magnet of relay F when thus energized completes by its armature 26 a circuit of battery 28 through magnet 30 of the alarm-indicating device H . While this device is conventionally illustrated as an ordinary telegraphic register, it is understood that other alarm-indicating devices may be used which are adapted to respond to the control of the relay F . A ground-indicating signal is provided and included in another circuit of battery 28, which is controlled jointly by relays F and F' . This signal may be the incandescent lamp 29 (shown in the drawings) or any other suitable signal adapt-

ed to respond to the control of its circuit through battery 28. This circuit is normally interrupted at armature 27 through the energization of relay F' and is adapted to be interrupted at armature 26 in case relay F becomes de-energized. The operation of the system is as follows: When an alarm-signal is to be sent, the operation of the alarm-sending mechanism at M intermittently interrupts the circuit of the line-limbs. At each interruption the relays F and F' are de-energized, and relay F controls by its armature 26 the circuit of magnet 30 of the alarm-indicating device H to give the required alarm indication. The armature 27 of relay F' is also retracted at each interruption engaging its back contact; but as at this time armature 26 is out of engagement with its front contact the circuit of signal 29 is not completed and no ground indication is given. This condition is indicated in the drawings of the apparatus associated with line B . It has been shown that both relays F and F' are energized by current flowing over the two line-limbs at all times except when an alarm-signal is to be sent. In case, however, either limb becomes accidentally grounded at a point intermediate of the two relays referred to a short circuit is formed between such point of grounding and the grounded or return side of the central battery. This short circuit while still allowing current to flow through relay F , thus maintaining its energization, will deprive relay F' of substantially all current, causing its de-energization. Under this condition the retraction of its armature 27 completes the circuit of the ground-signal device, which may be traced as follows: from battery 28 through armature 26 and its associated front contact, through armature 27 with its associated back contact, and through lamp 29 to the opposite side of the battery. This local circuit will be maintained as long as relay F' is de-energized and relay F remains energized, the alarm-indicating device H being unaffected, for the reason that its circuit is maintained in its normally closed condition through the continued attraction of armature 26. It will also be seen that if the accidental ground be located upon any portion of the circuit of the line-limbs except that extending from magnet F through limb 1 to its associated contact 23 the operation of the alarm-sending apparatus would still cause the alarm indication. Under such a condition the interruption of the circuit of relay F by the alarm-sending mechanism would allow the retraction of armature 26, thus opening and closing the circuit of magnet 30, causing the proper alarm indication. The retraction of armature 26 would also at each interruption open the circuit of lamp 29 through battery 28, thus giving a series of flashes which would positively indicate the condition of the circuit. While I have

shown a particular local-circuit arrangement and indicated diagrammatically certain mechanism in connection with the electromagnets of relays F and F', I do not wish to be limited to the precise circuit arrangements or signaling devices indicated. The structure is one in which the simultaneous energization of both magnets maintains the normal condition of the indicating devices, in which the de-energization of both magnets causes an alarm indication, but not a ground indication, and in which the simultaneous energization of the magnet associated with the active side of the central battery and de-energization of the magnet associated with the grounded side of the battery causes the ground indication without altering the normal condition of the alarm-indicating device. While I have shown the magnets as the relay-magnets F and F', it is obvious that these might be electromagnets acting jointly to control the display of suitable signals mechanically rather than by means of a local circuit and battery. Other arrangements of the ground-indicating device and alarm-indicating device responsive to the control as determined by the circuit conditions which I have outlined might be made without departing from the spirit of my invention, and I therefore do not wish to be limited to any particular arrangement controlled by the electromagnets, (indicated at F and F').

Fig. 2 indicates an alternative arrangement for the local circuits of the ground-indicator and alarm-indicator, the alarm-indicator in this case being in a normally open circuit rather than in a normally closed circuit, as shown in Fig. 1. It will be seen that under normal conditions both relays being energized the circuit of battery 28 through magnet 30 stands normally open at the back contact of armature 26, while the circuit of lamp 29 stands normally open at the back contact of armature 27. During the sending of an alarm-signal, both relays being simultaneously de-energized, the retraction of both armatures completes the circuit of magnet 30, as will readily be seen, causing the required alarm indication. If the circuit of the line-limbs becomes accidentally grounded, as has been previously described, the consequent retraction of armature 27 will complete the circuit of lamp 29, causing its illumination to indicate such ground; but if relay F be at the same time de-energized, as through the sending of an alarm-signal, the retraction of its armature 26 opens the circuit of lamp 29, preventing its illumination.

In Figs. 3 and 4 are indicated modifications of my invention as embodied in the well-known telephone-exchange system of what is known as the "three-wire" type. This system differs from that of the previous drawings with respect to the telephone-exchange apparatus in that the cut-off relay 3, asso-

ciated with one limb of the talking-circuit, is replaced by a cut-off relay 34, which is included in a strictly local circuit having separate spring-jack terminals 38 and corresponding plug-terminals 41. In its telephonic operation the subscriber calls in the usual manner by removing his receiver from its hook-switch, thus completing a circuit of the battery C through line-relay 4, the contacts of the cut-off relay 34, the line-limbs, and the substation instrument, thus energizing relay 4 and lighting the telephone-line lamp 5. When the operator inserts a plug, a circuit for the cut-off relay is completed from the battery C through resistance 45, lamp 17, plug and jack contacts 41 38, through the winding of relay 34 to the return side of the battery, thus energizing the relay 34 and under normal conditions causing the lamp 17 to be illuminated. Through the insertion of the plug current from battery C is now furnished to the line through the windings 46 and 47 of repeating-coil R, cord-strands 9 and 10, and the corresponding plug and jack contacts, and the subscriber being at his telephone the relay 42, which is included in strand 10, is energized and by its contact completes a circuit in shunt of lamp 17, which includes the resistance 44 and causes the extinguishment of the lamp. The operator listens, tests, and rings in the well-known manner and by plugging in completes similar circuits for the line of the subscriber who is to be called. The subscribers' circuits are thus inductively united for conversation by means of the repeating-coil rather than by the condensers, as in the system of Fig. 1. Either subscriber can cause the illumination of his supervisory lamp 17 or 18 by actuating his hook-switch, thus energizing or de-energizing the relay 42 or 43, and the illumination of both lamps constitutes the customary disconnect-signal. The manipulations of the operator and subscriber and the action of the signals governed thereby are thus seen to be the same as in the system previously illustrated. With reference to the alarm apparatus it will be noted that the relays F and F' instead of being serially included in the line-limbs, as in the system of Fig. 1, are here in bridge of the two limbs and are directly connected to the central battery C. The alarm-sending mechanism is indicated in simplified form at M'; but it will be understood that this mechanism is similar to that indicated or specified in connection with Fig. 1 and that while in Fig. 3 the alarm-sending mechanism is indicated as controlling contacts in one line-limb only it will be understood that similar contacts for the other line-limb may be controlled by the same mechanism. It will be seen in this view, Fig. 3, that as long as the circuit of the line-limbs remains normal the two relays are energized by current from battery C and that this energization is not interfered

with by any of the telephonic operations of the system. If the circuit of the line-limbs is opened as through the operation of the alarm-sending mechanism, both relays are 5 deenergized, controlling the local circuit of the alarm-indicating mechanism H in the manner required to indicate an alarm-signal; also, that if the circuit of the line-limbs becomes grounded at a point intermediate of 10 the two relays the consequent deenergization of relay F' will allow the retraction of armature 27, thus completing the circuit of battery 28 through lamp 29, causing its illumination to indicate the presence of such an accidental ground. It is to be noted that resistance 35 of Fig. 3 and resistance 39 of Fig. 4 are not ordinarily required in the telephonic operation of the exchange system indicated. Their interposition is required in the present 15 structure to avoid short-circuiting the relay F' through a direct connection to the return side of the battery in case the resistances are omitted.

It is to be understood that my invention 20 may be embodied in other telephone-exchange structures than those illustrated and described and that while in Fig. 1 I have shown the electromagnet-windings included serially in the line-limbs and in Fig. 3 in 25 bridge of the line-limbs that method of association may be employed which is best adapted to the particular exchange system under consideration.

Fig. 5 indicates means by which any line of 30 a telephone-exchange system may be provided with the special alarm apparatus. The two limbs of the line enter the exchange and terminate in the customary manner upon the distributing-rack K at terminals 50 and are ordinarily carried through 35 this rack by the jumper-wires (indicated at 51 and 52) to terminals 53, and thence by permanently-connected wires to the other apparatus of the switchboard system. The 40 energizing-windings of the magnets or relays F and F' are permanently wired to terminals 59 of the same or an adjacent section of the distributing-rack and are provided with the customary protective devices, (indicated at 45 58.) In case it is desired to associate these magnets and their controlled mechanism with any particular line the jumper-wires referred to are removed and connection is made with the terminals 59 by the two pairs 50 of jumpers, as indicated at 54 55 and 56 57. In case it were desired to shift the magnets and their associated mechanism to some other line it would only be necessary to disconnect these last-mentioned jumpers from 55 terminals 50 and 53 and transfer them to the corresponding terminals of the line to which the apparatus is to be shifted, removing its jumpers 51 and 52, as previously described. It will thus be understood by those skilled in 60 65 the art that this arrangement provides means

whereby any set of alarm-receiving mechanism may be interchangeably connected with any telephone-line circuit of the system in a neat and workmanlike manner and without disturbing any of the permanent wiring. 70

While several batteries C, D, and E are shown in the drawings, it will be understood that these may be one and the same battery and also that the various grounds indicated are or may be replaced by a common return-wire connected with the grounded terminal of the central battery. It will also be evident to those skilled in the art that various modifications of my invention may be made without departing from its spirit, and I 75 therefore do not wish to be limited to the precise structures shown and described; but

I claim—

1. In a telephone-exchange system the combination of a normally closed metallic 80 telephone-line including a source of current at the exchange, electromagnetic mechanism having an energizing-winding in circuit with each line-limb and said source of current, means for intermittently interrupting 85 the circuit of the line in a predetermined manner and an alarm-indicating device controlled by said mechanism adapted to respond to interruptions of current in both windings. 90

2. In a telephone-exchange system the combination of a normally closed metallic 95 telephone-line including a source of current at the exchange, electromagnetic mechanism controlled by two energizing-windings, one 100 winding being associated with each line-limb respectively, means for intermittently interrupting the circuit of the line in a predetermined manner and a ground-indicating device controlled by said mechanism adapted to respond to an interruption of current in 105 one winding only.

3. In a telephone-exchange system the combination of a normally closed metallic 110 telephone-line including a source of current at the exchange, electromagnetic mechanism controlled by two energizing-windings, one winding being associated with each line-limb respectively, means for intermittently interrupting the circuit of the line in a predetermined manner, an alarm-indicating device 115 controlled by said mechanism adapted to respond to interruptions of current in both windings and a ground-indicating device controlled by said mechanism adapted to respond to an interruption of current in one 120 winding only.

4. In a telephone-exchange system the combination of a normally closed metallic 125 telephone-line including a source of current at the exchange, electromagnetic mechanism controlled by two energizing-windings, one winding being associated with each line-limb respectively, means for intermittently interrupting the circuit of the line in a predetermined manner and means whereby the 130

interruption of current in one winding will cause a ground indication.

5. In a telephone-exchange system the combination of a normally closed metallic 5 telephone-line including a source of current at the exchange, electromagnetic mechanism controlled by two energizing-windings, one winding being associated with each line-limb respectively, means for intermittently 10 interrupting the circuit of the line in a pre-determined manner and means whereby the interruption of current in both windings will cause an alarm indication.

15 6. In a telephone-exchange system the combination of a normally closed metallic telephone-line including a source of current at the exchange, electromagnetic mechanism controlled by two energizing-windings, one winding being associated with each line-limb
20 20 respectively, means for intermittently interrupting the circuit of the line in a predetermined manner and means whereby the interruption of current in one winding will cause a ground indication and the interruption of current in both windings will cause an alarm indication.
25

7. In a telephone-exchange system the combination of a normally closed metallic telephone-line including a source of current

30 at the exchange, electromagnetic mechanism controlled by two energizing-windings, one winding being associated with each line-limb respectively, means for intermittently interrupting the circuit of said windings in a pre-determined manner and a ground-indicating device controlled by said mechanism adapted to respond to an interruption of current in one winding only.

35

8. In a telephone-exchange system the combination of a normally closed metallic telephone-line including a source of current at the exchange, electromagnetic mechanism controlled by two energizing-windings, one winding being associated with each line-limb respectively, means for intermittently interrupting the circuit of said windings in a pre-determined manner, an alarm-indicating device controlled by said mechanism adapted to respond to interruptions of current in both windings and a ground-indicating device controlled by said mechanism adapted to respond to an interruption of current in one winding only.

40 combination of a normally closed metallic telephone-line including a source of current at the exchange, electromagnetic mechanism controlled by two energizing-windings, one winding being associated with each line-limb

45 respectively, means for intermittently interrupting the circuit of said windings in a pre-determined manner, an alarm-indicating device controlled by said mechanism adapted to respond to interruptions of current in both

50 windings and a ground-indicating device controlled by said mechanism adapted to respond to an interruption of current in one winding only.

9. In a telephone-exchange system the combination of a normally closed metallic telephone-line including a source of current at the exchange, electromagnetic mechanism controlled by two energizing-windings, one winding being associated with each line-limb 55 respectively, means for intermittently interrupting the circuit of said windings in a pre-determined manner and means whereby the interruption of current in one winding will cause a ground indication. 60

65 10. In a telephone-exchange system the

combination of a normally closed metallic telephone-line including a source of current at the exchange, electromagnetic mechanism controlled by two energizing-windings, one winding being associated with each line-limb respectively, means for intermittently interrupting the circuit of said windings in a predetermined manner and means whereby the interruption of current in both windings will cause an alarm indication. 75

11. In a telephone-exchange system the combination of a normally closed metallic telephone-line including a source of current at the exchange, electromagnetic mechanism controlled by two energizing-windings, one winding being associated with each line-limb respectively, means for intermittently interrupting the circuit of said windings in a pre-determined manner and means whereby the interruption of current in one winding will cause a ground indication and the interruption of current in both windings will cause an alarm indication. 80 85

12. In a telephone-exchange system the combination of a normally closed metallic 90 telephone-line including a source of current at the exchange, electromagnetic mechanism controlled by two energizing-windings, one winding being associated with each line-limb respectively, means for intermittently interrupting the circuit of said source of current in a predetermined manner and a ground-indicating device controlled by said mechanism 95 adapted to respond to an interruption of current in one winding only.

13. In a telephone-exchange system the combination of a normally closed metallic telephone-line including a source of current at the exchange, electromagnetic mechanism controlled by two energizing-windings, one winding being associated with each line-limb respectively, means for intermittently interrupting the circuit of said source of current in a predetermined manner, an alarm-indicating device controlled by said mechanism adapted to respond to interruptions of current in both windings and a ground-indicating device controlled by said mechanism adapted to respond to an interruption of current in one winding only. 105 110 115

14. In a telephone-exchange system the combination of a normally closed metallic telephone-line including a source of current at the exchange, electromagnetic mechanism controlled by two energizing-windings, one winding being associated with each line-limb respectively, means for intermittently interrupting the circuit of said source of current in a predetermined manner and means whereby the interruption of current in one winding will cause a ground indication. 125

15. In a telephone-exchange system the combination of a normally closed metallic telephone-line including a source of current at the exchange, electromagnetic mechanism 130

controlled by two energizing-windings, one winding being associated with each line-limb respectively, means for intermittently interrupting the circuit of said source of current in a predetermined manner and means whereby the interruption of current in both windings will cause an alarm indication.

16. In a telephone-exchange system the combination of a normally closed metallic telephone-line including a source of current at the exchange, electromagnetic mechanism controlled by two energizing-windings, one winding being associated with each line-limb respectively, means for intermittently interrupting the circuit of said source of current in a predetermined manner and means whereby the interruption of current in one winding will cause a ground indication and the interruption of current in both windings will cause an alarm indication.

17. In a telephone-exchange system the combination of a normally closed metallic telephone-line including a source of current at the exchange, electromagnetic mechanism controlled by two energizing-windings, one winding being associated with each line-limb respectively, an alarm-sending device adapted to intermittently interrupt the circuit of the line in a predetermined manner and a ground-indicating device controlled by said mechanism adapted to respond to an interruption of current in one winding only.

18. In a telephone-exchange system the combination of a normally closed metallic telephone-line including a source of current at the exchange, electromagnetic mechanism controlled by two energizing-windings, one winding being associated with each line-limb respectively, an alarm-sending device adapted to intermittently interrupt the circuit of the line in a predetermined manner, an alarm indicating device controlled by said mechanism adapted to respond to interruptions of current in both windings and a ground-indicating device controlled by said mechanism adapted to respond to an interruption of current in one winding only.

19. In a telephone-exchange system the combination of a normally closed metallic telephone-line including a source of current at the exchange, electromagnetic mechanism controlled by two energizing-windings, one winding being associated with each line-limb respectively, an alarm-sending device adapted to intermittently interrupt the circuit of the line in a predetermined manner and means whereby the interruption of current in one winding will cause a ground indication.

20. In a telephone-exchange system the combination of a normally closed metallic telephone-line including a source of current at the exchange, electromagnetic mechanism controlled by two energizing-windings, one winding being associated with each line-limb respectively, an alarm-sending device adapt-

ed to intermittently interrupt the circuit of the line in a predetermined manner and means whereby the interruption of current in both windings will cause an alarm indication.

21. In a telephone-exchange system the combination of a normally closed metallic telephone-line including a source of current at the exchange, electromagnetic mechanism controlled by two energizing-windings, one winding being associated with each line-limb respectively, an alarm-sending device adapted to intermittently interrupt the circuit of the line in a predetermined manner and means whereby the interruption of current in one winding will cause a ground indication and the interruption of current in both windings will cause an alarm indication.

22. In a telephone-exchange system the combination of a normally closed metallic telephone-line including a grounded source of current at the exchange, an energizing-winding associated with that line-limb leading from the active terminal of said source and an energizing-winding associated with that line-limb leading from the grounded terminal of said source, an alarm-sending device adapted to intermittently interrupt the circuit of said windings in a predetermined manner, and mechanism controlled by the first-mentioned winding adapted to 95 actuate an alarm-indicator.

23. In a telephone-exchange system the combination of a normally closed metallic telephone-line including a grounded source of current at the exchange, an energizing-winding associated with that line-limb leading from the active terminal of said source and an energizing-winding associated with that line-limb leading from the grounded terminal of said source, an alarm-sending device adapted to intermittently interrupt the circuit of said windings in a predetermined manner and mechanism controlled by both windings adapted to control the display of a ground-indicator.

24. In a telephone-exchange system the combination of a normally closed metallic telephone-line including a grounded source of current at the exchange, an energizing-winding associated with that line-limb leading from the active terminal of said source and an energizing-winding associated with that line-limb leading from the grounded terminal of said source, an alarm-sending device adapted to intermittently interrupt the circuit of said windings in a predetermined manner, mechanism controlled by the first-mentioned winding adapted to actuate an alarm-indicator and mechanism controlled by both windings adapted to control the display of a ground-indicator.

25. In a telephone-exchange system the combination of a normally closed metallic telephone-line including a grounded source of current at the exchange, an energizing-

- winding associated with that line-limb leading from the active terminal of said source and an energizing-winding associated with that line-limb leading from the grounded 5 terminal of said source, an alarm-sending device adapted to intermittently interrupt the circuit of said windings in a predetermined manner and mechanism controlled by the said windings whereby the interruption of 10 current in one winding only will cause the actuation of a ground-indicator and the interruption of current in both windings will cause the actuation of an alarm-indicator.
26. In a telephone-exchange system the 15 combination of a normally closed metallic telephone-line including a grounded source of current at the exchange, an energizing-winding associated with that line-limb leading from the active terminal of said source and 20 an energizing-winding associated with that line-limb leading from the grounded terminal of said source, an alarm-sending device adapted to intermittently interrupt the circuit of said windings in a predetermined 25 manner, mechanism controlled by the first-mentioned winding adapted to actuate an alarm-indicator and means whereby an in-

terruption of current in the last-mentioned winding will cause a ground indication.

27. In a telephone-exchange system the 30 combination of a normally closed metallic telephone-line including a grounded source of current at the exchange, an energizing-winding associated with that line-limb leading from the active terminal of said source 35 and an energizing-winding associated with that line-limb leading from the grounded terminal of said source, an alarm-sending device adapted to intermittently interrupt the circuit of said windings in a predetermined 40 manner, mechanism controlled by the first-mentioned winding adapted to actuate an alarm-indicator and means associated with said windings whereby the grounding of either line-limb at a point intermediate of the two windings will cause the actuation of 45 a ground-indicator without actuating the alarm-indicator.

In witness whereof I hereunto subscribe my name this 14th day of October, A. D. 1904.

HARRY G. WEBSTER.
